Primary Examiner — Christy Nemeth(74) *Attorney, Agent, or Firm* — Carmel Patent Agency;
Robert Ballarini(57) **CLAIM**

The ornamental design for a travel charging case as shown and described.

DESCRIPTION

1. Travel charging case

1.1 is a top perspective view of a travel charging case, shown in a closed configuration;

1.2 is a top plan view thereof;

1.3 is a right-side elevation view thereof;

1.4 is a left-side elevation view thereof;

1.5 is a front elevation view thereof;

1.6 is a back elevation view thereof;

1.7 is a bottom plan view thereof; and

1.8: is a top plan view of the travel charging case, shown in an open configuration.

The features shown in broken lines in the drawing figures form no part of the claimed design.

The travel charging case is used for charging, storing and transporting a sonic toothbrush.

1 Claim, 8 Drawing Sheets(56)
